OUTDOOR THEATER LOUD-SPEAKER UNIT

Horace E. Shock, Lima, Ohio

Application January 29, 1948, Serial No. 144,125

Term of patent 3½ years

(Cl. D26—14)

To all whom it may concern:

Be it known that I, Horace E. Shock, a citizen of the United States, and resident of Lima, in the county of Allen and State of Ohio, have invented a new, original, and ornamental Design for an Outdoor Theater Loud Speaker Unit, of which the following is a specification, reference being had to the accompanying drawing, forming a part thereof.

In the drawings, Fig. 1 is a perspective view of an outdoor theater loud speaker unit showing my new design; Fig. 2 is a view similar to Fig. 1 with one of the speaker units removed to show the front face thereof; and Fig. 3 is a top plan view.

I claim:

The ornamental design for an outdoor theater loud-speaker unit, substantially as shown.

HORACE E. SHOCK.
